UNITED STATES PATENT OFFICE

SAMUEL A. NEIDICH, OF EDGEWATER PARK, NEW JERSEY

TUBE AND METHOD OF FORMING THE SAME

Application filed November 14, 1928. Serial No. 319,273.

My invention relates to the production from celluloid, cellulose nitrate, cellulose acetate, other products of cellulose, or any suitable substance, of ornamental tubes which 5 may be used for fountain pen or pencil casings, umbrella handles, etc.

As hereinafter described, the essential feature of my invention is the formation of a pattern upon the outer surface of an inner tube, for instance, by recessing such tube and filling the recess with visibly different pattern material, removing the surplus filling material, and thus causing the surface of the tube to afford a mosaic effect. The inner tube 15 thus treated may be covered with an outer tube of translucent or transparent material thru which the pattern is visible.

My invention includes the various novel features of construction, arrangement, and 20 procedure hereinafter more definitely specified.

In said drawings; Fig. I is a transverse sectional view of a tube conveniently embodying my invention.

25 Fig. II is a cross sectional view of the inner tube shown in Fig. I with a diagrammatic representation of means for forming a pattern thereon.

Fig. III is a cross sectional view of said 30 inner tube shown in Figs. I and II, but with the filling material applied thereto.

Fig. IV is a cross sectional view of said tube shown in Fig. III, but with the surplus 35 filler material removed.

Fig. V is a perspective view of a fountain 40 pen cap embodying a form of my invention.

Referring to Fig. I; the inner tube 1 may be formed of any suitable material such as above indicated, by boring a solid rod, extruding the material in initially tubular form, or forming the tube by rolling a primarily plane sheet, or otherwise. Said tube 1 has pattern recesses 2 formed in the perimeter thereof which are filled with a primarily plastic pattern substance 3 which becomes rigid after it is applied. For instance, said filling pieces 3 may be the residue of any of the substances aforesaid which have been dissolved in a suitable solvent and applied in 50 a plastic condition. For instance, acetone is

a suitable solvent for celluloid and cellulose nitrate, and ethyl acetate, or a mixture of alcohol and ether are suitable solvents for cellulose acetate. The latter is preferable to celluloid, because it is noninflammable. 55 The outer tube 5 shown in Fig. I may be formed in any manner above contemplated, and is rigidly connected with the inner tube 1 and the pattern filling pieces 3. Altho I have shown dividing lines between the parts 60 1, 3, and 5; it is to be understood that when said parts are caused to adhere by being moistened with a suitable solvent, they are integrated as if formed of one piece. For instance, both the inner and outer tubes 1 and 5 may be formed of respective sheets of celluloid rolled while moistened with acetone and preferably while submerged in a bath including such solvent, in accordance with the disclosures of Letters Patent of the United 65 States No. 1,661,451 granted to John N. Whitehouse March 6, 1928.

It is to be understood that the materials above contemplated may include any material or coloring to render them fanciful. For instance, celluloid and the like may be clear or colored to any tint or shade without inclusion of any material producing a clouded effect, but such effect may be produced by the inclusion of powdered aluminum or other powder, metallic or otherwise; for instance, what is known as fish scale powder, suspended in clear celluloid affords an iridescent appearance to the latter closely resembling mother of pearl. 75 80 85

I find it convenient to form the pattern upon the periphery of the tube 1 by such means as indicated in Fig. II, to wit, a die 7 having cameo pattern members 8 projecting therefrom. Said die is conveniently mounted upon the holder 9 which may be rocked or rotated upon its shaft 10, with said die in rolling contact with said tube 1, to form the intaglio pattern marks 2 therein, in conformity with the projections 8. 90 95

As indicated in Fig. III; the pattern recesses 2 in the inner tube 1 may be filled with the primarily plastic pattern material 3 of the character above contemplated; said pattern filler material 3 being visibly dif- 100

ferent from the material of said tube 1. Said tube 1 may be formed of opaque material, or, if translucent, may have the inner circumference or convolution 12 thereof opaque, to 5 conceal the contents of the tube, such as black ink in a fountain pen or the metal or wood of an umbrella stick. The opaque portion of said tube 1 may be in unitary relation with the sheet from which such a tube may be 10 formed or may be primarily separate.

Altho said pattern filler material 3 is plastic when applied to the inner tube 1; it quickly sets to rigid form in coherent relation with said tube, and the surplus portion thereof may 15 be ground off or otherwise removed to leave the tube 1 with the finished outer surface as indicated in Fig. IV. Such tubes may be used for any purpose, without the outer protecting tube 5, but the latter enhances the 20 beauty of the interior tube by refraction and reflection of light. The outer tube 5 may be formed upon the inner tube 1, in any way above contemplated, but, in the completed form shown in Fig. I, is in permanently rigid 25 relation with the inner tube.

Referring to Fig. V; the fountain pen cap 14 may include a tube formed as above described, wherein the pattern recesses 2 have the respective configuration of game card 30 spots and the pattern filling material 3 is colored to represent such spots; such a structure being desirable, for instance, as a bridge game prize.

However, I do not desire to limit myself to 35 the precise details of construction, arrangement, or method of operation herein set forth, as it is obvious that various modifications may be made therein without departing from the essential features of my invention, as defined in the appended claims.

I claim:

1. The method of making a tube, which comprises forming an inner tube; making a 45 pattern recess in the outer surface of that tube; filling that recess with visibly different material; removing surplus filling material; and applying an outer tube of translucent material, thru which the pattern is visible.

50 2. A tube comprising an inner tube having a pattern recess in its periphery, and a filling of visibly different pattern material in said recess and covered by an outer translucent tube formed of a cellulose product.

55 3. A tube formed of inner and outer tubes of cellulose products, with the rigid residue of a primarily plastic cellulose product pattern material between them.

4. A tube as in claim 3; wherein the outer 60 tube is translucent and the pattern material visible therethru.

5. A tube as in claim 3; wherein the inner tube is opaque.

65 6. A tube as in claim 3; wherein the outer tube is translucent and the pattern material

is visible therethru, and the inner tube is opaque.

In testimony whereof, I have hereunto signed my name at Burlington, New Jersey, this thirty-first day of October, 1928.

SAMUEL A. NEIDICH.
